UNITED STATES PATENT OFFICE

143,877

DESIGN FOR A PIN OR SIMILAR ARTICLE

Oreste Pennino, New York, N. Y.

Application September 6, 1945, Serial No. 121,882

Term of patent 3½ years

(Cl. D45—19)

To all whom it may concern:

Be it known that Oreste Pennino, citizen of United States and resident of New York city, in the county of Queens and State of New York, has invented a new, original, and ornamental Design for a Pin or Similar Article, of which the following is a specification, reference being had to the accompanying drawing, forming part thereof, and in which

Fig. 1 is a top plan view of a pin embodying my new design; and

Fig. 2 is a side elevational view of the same.

I claim:

The ornamental design for a pin or similar article, substantially as shown.

ORESTE PENNINO.
